METHOD OF MOUNTING UNDERNEATH
EQUIPMENT TO RAILROAD CARS

Karl F. Nystrom, Milwaukee, Wis.

Application April 10, 1937, Serial No. 136,081

1 Claim. (Cl. 105—2)

My invention relates more especially to the method of applying what is known as the underneath equipment on railroad passenger cars and particularly to passenger cars of the present day construction; and has for its object the provision of a car wherein the center of gravity is materially lower than in car constructions as at present in use and hence a car wherein the element of safety is greatly increased.

10 The invention also has for its object the provision of a railroad passenger car wherein the necessary underneath equipment is so arranged and applied that the weight is properly balanced and while at the same time means is employed 15 whereby the air resistance is very materially reduced.

A further object and advantage of my improvement is the provision of a better riding and easier pulling car wherein the distribution of 20 weight is more properly accomplished and as a result the problem of proper spring equipment in turn is greatly simplified.

The objects and advantages of my invention will all be more readily comprehended from the 25 detailed description of the accompanying drawing wherein:

Figure 1 is a cross-sectional diagrammatic illustration or outline of a passenger car body with center sills illustrating my improved means and 30 method of applying the underneath equipment.

Figure 2 is an inverted plan of the structure as illustrated in Figure 1.

Figure 3 is a side elevation of a portion of the 35 bottom and center sills of the car with my improved method and enclosure means.

My invention relates to the method of applying the underneath equipment on railroad passenger cars of present day construction involving the ideas of stream-lining so as to overcome 40 air resistance in order that greater speed may be obtained.

As the invention relates entirely to the method and means of applying the equipment underneath the car, a diagrammatic cross-section outline of 45 the car body, as shown at 10 in Figure 1, will suffice for the purpose of illustrating my improved idea which consists in applying and securing the usual underneath equipment of passenger cars in a manner designed to effect a greater 50 balance and at the same time so as to materially lower the center of gravity and thereby enhance the safety of the car.

The method as shown in the drawing consists 55 in providing the bottom of the center sills 11, 11 intermediate of the body bolsters adjacent oppo-

site ends, with means or a member 12 of width slightly greater than the combined spacing and width of the center sill members and of length less than the distance between the body bolsters and yet sufficient to accommodate the usual underneath equipment of railroad passenger cars; the member 12 being firmly secured in any suitable manner to the bottom of the center sill members 11.

In practice, the floor of the car is first constructed on top of the center sill members and body bolsters and this assembled construction is then inverted so the center sills are presented upwardly; the floor unit or structure being supported on the floor of a shop in any suitable manner. The holding member 12 is then secured to the center sill members between the body bolsters, with the plate equally disposed to opposite sides of the center sill members as disclosed in Figure 1.

After the member 12 has been attached to the center sill members, the passenger car underneath equipment is then applied to member 12 which is rigidly secured to the center sill members. The equipment is schematically outlined 25 in dotted lines in Figure 2; this equipment generally consisting of the steam heat vapor regulator indicated at 13—an air cooling unit indicated at 14—water reservoirs indicated at 15—air 30 brake valves as at 16—air brake reservoirs at 17—a battery box at 18—and a second steam heat regulator at 13.

After the various elements, as outlined above, have been grouped on member 12 and riveted or otherwise rigidly secured in place, the entire 35 grouping is then preferably enclosed by a suitable housing 19 consisting of a bottom, two side walls and two end walls, the lower end portions whereof are given arcuate formation as indicated at 20 in Figure 2; while the upper portions are 40 preferably somewhat extended as at 21, 21 with sloping walls 22 at the ends. The extended ends 21 are secured to the center sills 11. The ends of the housing are preferably shown with a slight upward slope as at 23 in Figure 3 where the arcuate end walls begin, thus affording less resistance 45 to air pressure.

The side walls of the housing at proper points are, of course, provided with suitable closable 50 openings whereby access to the equipment within the housing may be had when occasion requires.

After the floor unit has been equipped with the equipment as described and the housing applied about the equipment, the floor unit is then 55 reversed and the equipment and center sills will

then depend therebeneath within the enclosure 18 as shown in Figure 1; the car body is then assembled and applied to the floor unit.

In the conventional method of installing the 5 underneath equipment but little of the equipment is mounted on the center sill. This equipment, in cars as heretofore constructed, was distributed more or less over the entire bottom of the car, with the battery box (outlined at 18 10 in Figure 2) usually located near an end wall of the car, the air conditioning or cooling unit (generally outlined at 14 in Figure 2) being located on the opposite side of the center sills, namely in proximity to the other side sill; while 15 the air reservoirs, air brake valves, and water reservoirs were scattered over the bottom of the car as convenience or room permitted.

It is apparent that such disposition of the equipment made it quite difficult to build a 20 stream-line car adapted to offer the minimum of resistance to air. Such scattered mounting of the underneath equipment also greatly disturbed or disrupted the proper balance of the car. Such arrangement of the equipment in 25 certain types of stream-line cars also resulted in loss of space intermediate of the floor and the under curved side walls of the car.

With my improved means and method the equipment is now entirely supported by and suspended 30 beneath the center sills of the car thus appreciably lowering the center of gravity of the car. Furthermore, the equipment is so applied to the center sills as to perfectly balance the weight transversely; the equipment with its enclosure or housing being all disposed adjacent the longitudinal center line of the car and intermediate of the body bolsters as well as being disposed in a vertical plane considerably removed from the vertical plane of the side sills 35 40 or side walls of the car. By concentrating the equipment in the manner disclosed and covering the equipment with a suitable housing provided with arcuate end walls and upwardly sloping bottom as described, a very material reduction 45 in air resistance is not only obtained, but at the same time the equipment is protected from injury due to flying rocks, etc. The method of arrangement also provides for an enclosure or housing of minimum cross sectional area.

50 A car with my improved method of under-

neath equipment mounting and the enclosure means or housing, wherein the weight is confined to the longitudinal center line of the car, results in a car of greater safety due to the fact that the entire car body structure is counterbalanced and the center of gravity lowered to quite a degree. With the equipment arranged and housed as described, the underneath structure practically functions like the keel of a boat--an action very noticeable in high speed trains 10 with the result that a better riding car is obtained because of the better distribution of weight; this distribution also simplifying the usual problems of spring application.

My method of arrangement provides a car 15 which is more easily operated or drawn because of the minimum cross-sectional area of the bottom of the car and the resultant reduction in air resisting surfaces.

As my invention does not relate to the car 20 body construction above the floor unit, detail illustration and explanation of general car construction above the center sills and floor is not deemed necessary for a proper understanding of my invention.

The exemplification is believed to be the best embodiment of the invention although certain modifications of details may be made without departing from the spirit of the invention.

What I claim is:

In combination with the center sill members of a standard railroad car, a rigid single piece equipment holding element adapted to be secured centrally to the bottoms of the center sill members of the car underframe and of width less than the width of the car floor, said element being adapted to have all of the car underneath equipment uniformly secured thereto and disposed at opposite sides of and adjacent to the longitudinal center line of the car body so as to locate the weight of said underneath equipment adjacent said longitudinal center line and symmetrically disposed with respect to the longitudinal center line of the car body and in counterbalancing relation with the weight of the car body, and a closed housing coextensive with said element and enclosing all of the car underneath equipment, said housing being provided with reduced air deflecting ends.

KARL F. NYSTROM. 50
